UNITED STATES PATENT OFFICE

CHARLES C. SPREEN, OF DETROIT, MICHIGAN, ASSIGNOR TO KELVINATOR CORPORATION, OF DETROIT, MICHIGAN, A CORPORATION OF MICHIGAN

REFRIGERATION

Application filed November 5, 1926. Serial No. 146,386.

My invention relates to refrigeration, and particularly to refrigerator cabinets, and to the doors thereof, and the principal object of my invention is to provide a new and improved refrigerator cabinet door. In the drawings accompanying this specification and forming a part of this application I have shown, for purposes of illustration, two forms which my invention may assume. In 10 these drawings:

Figure 1 is a partial front elevation of a cabinet showing a door embodying one form of my invention.

Figure 2 is an enlarged section on the line 15 2—2 of Figure 1, while

Figure 3 is a section similar to Figure 2 illustrating a second form which my invention may assume.

The embodiment of my invention shown 20 in Figures 1 and 2 comprises a door 11 provided to close the opening 12 in the refrigerator cabinet 13, and itself consisting essentially of a sheet metal inner facing 14 and a sheet metal outer facing 15, with the space 25 therebetween filled with suitable heat insulating material 16, such as metal wool, with the two facings 14 and 15 having their edges 17 and 18 substantially abutting along the peripheral edge of the door 11, and with the 30 two facings 14 and 15 secured together, heat insulated from each other, and the door accordingly integrated without conducting connection between the facings 14 and 15, by an annular member 19 formed of suitable heat 35 insulating material, such as wood, connected to the inner facing 14 by means of a plurality of nails 20 extending through the edge 17 of the inner facing 14 into the annular member 19, and secured to the outer facing 15 by 40 curling the edge 18 of the outer facing 15 about a projecting rib 21 on the annular member 19 with the inner edge 18 of the outer facing 15 terminating short of engagement with the edge 17 of the inner facing 14.

45 Mounted on the inner face 22 of the rib 21, by means of suitable nails 23, is a resilient member 24 serving to tightly seal the space between the door 11 and the cabinet 13, while the door 11 is supported from the cabinet 50 13 by means of hinges 25 secured to the

cabinet 13 by means of suitable wood screws 26, and to the door 11 by means of similar wood screws 27 extending through the outer facing 15 into the annular member 19, and the door 11 is held in closed position by means of a latch 28 similarly secured to the cabinet 13, and to the door 11.

The embodiment of my invention shown in Figure 3 comprises a door 31 provided to close the opening 32 in the refrigerator cabinet 33, and itself consisting essentially of sheet metal inner facing 34 and a sheet metal outer facing 35, with the space therebetween filled with suitable heat insulating material 36, such as metal wool, with the two facings 34 and 35 having their edges 37 and 38 substantially abutting along the peripheral edge of the door 31, and with the two facings 34 and 35 secured together, heat insulated from each other, and the door accordingly integrated without conducting connection between the facings 34 and 35, by an annular member 39 formed of suitable heat insulating material, such as wood, connected to the inner facing 34 by curling the edge 37 into 70 an annular groove 40 formed in the annular member 39, and secured to the outer facing 35 by curling the edge 38 of the outer facing 35 about a projecting rib 41 on the annular member 39 with the inner edge 38 of the outer facing 35 terminating short of engagement with the edge 37 of the inner facing 34.

75 Mounted on the inner face 42 of the rib 41, by means of suitable nails 43, is a resilient member 44 serving to tightly seal the space between the door 31 and the cabinet 33, while the door 31 is supported from the cabinet 33 by means of suitable hinges 45 secured to the cabinet 33 by means of suitable wood screws 46, and to the door 31 by means of similar 80 wood screws 47 extending through the outer facing 35 into the annular member 39, and the door 31 is held in closed position by means of a latch similarly secured to the cabinet 33, and to the door 31.

85 From the above description it will be obvious to those skilled in the art that I have provided a refrigerator door accomplishing at least the principal object of my invention.

90 At the same time it will also be obvious 100

to those skilled in the art that the particular embodiments of my invention herein shown and described embody advantages other than those particularly pointed out herein, and that the embodiments of my invention herein shown and described may be variously changed and modified without departing from the spirit of my invention or sacrificing the advantages thereof, and it will therefore be understood that the disclosure herein is illustrative only, and that my invention is not limited thereto.

10 I claim:

15 A door for refrigerator cabinets comprising a frame member formed of heat insulating material, a rib extending laterally from the front of said frame member and provided with spaced grooves, a sheet metal outer facing enclosing the front of said frame member and said rib, and a sheet metal inner facing substantially enclosing the remainder of said frame member, the edges of each of said facings projecting into the grooves in said rib.

20 25 In testimony whereof I hereunto affix my signature.

CHARLES C. SPREEN.
